United States Patent Office

Des. 198,874
Patented Aug. 11, 1964

198,874

PACKAGE COVER

Richard Leo Joosten, Elmhurst, Ill., assignor to American Can Company, New York, N.Y., a corporation of New Jersey

Filed Apr. 22, 1963, Ser. No. 74,550

Term of patent 14 years

(Cl. D58—26)

The figure is a perspective view of a package cover showing my new design. Except for the absence of a tab the sides not shown are the same as those shown.

I claim:

The ornamental design for a package cover, substantially as shown and described.
